U. J. RAYMOND

LOG TURNER

Filed Dec. 16. 1922

Inventor

Ulrick J. Raymond

By H. L. & C. L. Reynolds
Attorneys

UNITED STATES PATENT OFFICE.

ULRICK J. RAYMOND, OF SEATTLE, WASHINGTON.

LOG TURNER.

Application filed December 16, 1922. Serial No. 607,292.

To all whom it may concern:

Be it known that I, ULRICK J. RAYMOND, a citizen of the United States of America, and resident of the city of Seattle, in the county of King and State of Washington, have invented certain new and useful Improvements in Log Turners, of which the following is a specification.

My invention relates to log turners such as are used in saw mills, particularly at the head saw, for turning and handling logs upon the set-works carriage. These devices are sometimes termed niggers.

The principal object of my invention is to provide a nigger or log turner which will ordinarily be rigid but which will have sufficient inherent flexibility that it will not be broken by a continuation of the log's end-wise movement after its engagement by the log turner.

A further object is the provision of means for adjusting the degree of flexibility of these arms.

A further object is the provision of means permitting easy and quick replacement of a broken log turning arm.

A further object is the provision of means whereby the parts of the log turning arm may be quickly disassembled for inspection or repair.

My invention comprises those novel parts and combinations thereof which are shown in the accompanying drawings, described in the specification, and particularly defined by the claims terminating the same.

In the accompanying drawings I have shown my invention in the form which is now preferred by me.

Figure 1 is a perspective view of a set-works carriage and my log-turner shown operating upon a log carried upon the carriage.

Figure 2 is a plan view and partial section through my log-turning arm.

The log turners most commonly employed in connection with saw mill set-works require that the set-works carriage be brought to a dead stop prior to engagement of the log turner arm with the log, for otherwise the log turning arm, being itself rigid and being rigidly mounted, may be broken. The necessity for bringing the carriage to a dead stop tends to slow up the work and consequently the whole mill, for the speed of operation of the mill depends, in large meas-

ure, on the speed of the head saw. Further, the necessity of replacing broken log turning arms causes entire suspension of work at the head saw for a considerable period of time. This is a matter of somewhat frequent occurrence in the desire to speed up work by engaging the log with the turning arm at the instant the carriage comes to a stop, and the consequent misjudging of the speed of the carriage and engagement of the log prior to its complete stoppage. By the use of my device it is possible to engage the log with the turning arm prior to the carriage coming to a stop, and in fact to start turning the log prior to stopping the carriage, and this without danger of breakage of the turning arm. The increase in speed which is permitted by this arrangement will be obvious.

As is common practice in present log turners, a swinging arm or arms 1 is mounted upon a shaft 10, and upon the outer end of this arm 1 is supported the log engaging arm, the latter, and the arm 1, being operated through a piston rod 11 directly connected thereto. It is also common practice to secure on the shaft 10, to oscillate freely thereon, bumper arms 12, these being controlled through a second piston rod 13 directly connected to the bumper arms. The latter, however, form no part of my invention and are only included in the drawing for the purpose of better illustration. The shaft 10 is mounted parallel to the tracks 21 upon which the set-works carriage 2 is movable. The log L is supported upon head blocks 22 extending transversely of the carriage and is held in position thereon by knees 23.

The log-engaging arm is similar to log engaging arms now employed in connection with apparatus of the type heretofore described, except that it is formed in two parts instead of being a single rigid arm. The inner part 3 is the supporting part and is pivoted in the arm or arms 1 at 31. An extension 30 may be provided, as is common, to which is connected the piston rod 11 to control the movement of the log-engaging arm. In its outer end the inner or supporting part 3 is provided with a recess 32. Within this recess fits the inner end of the outer part 4 of the log-turning arm. The outer end of the part 4, as is common, is provided with a hook or dog 41, which is

the portion that actually engages the log to turn it.

The two parts 3 and 4 are pivotally connected, a pivot pin 34 being passed through the outer end of the inner part 3 and the inner end of the outer part 4 in such manner that the outer part 4 may swing relative to the inner part 3 in the direction of movement of the log L and carriage 2.

10 The two parts 3 and 4 are normally maintained in alignment with each other. The inner part 3 is provided adjacent to its swinging end with two lateral bosses 33 which are provided with internal pockets 35 opening into opposite sides of the central recess 32. An apertured cap 36 is preferably secured to the outer extremity of each of the bosses 33 for the purpose of closing the outer ends of the pockets 35, 20 the caps 36 being readily removable. A bolt 37 is passed freely through the aperture in each cap 36, and an internal adjusting nut 38 is threaded on each of the bolts 37, the nuts 38 serving to limit inward movement of the bolts 37. A spring retainer 39 is secured to the inner end of each of the bolts 37 within the corresponding recess 32. A helical compression spring 5 is interposed between each spring retainer 39 and the corresponding cap 36.

25 The retainers 39 of the bolts 37 are arranged to bear upon opposite sides of the inner end 43 of the outer part 4, inwardly of its pivot pin 34. By properly adjusting the tensions upon the compression springs 5 through the nuts 38, the outer part 4 may be held in line with the inner part 3 to move in a common plane except when the outer end of the part 4 is moved from 40 that plane, as by engagement with a moving log L. This has been indicated by dot-and-dash lines in Figure 1. If desired to remove either or both of the springs 5, this may be accomplished by removing the corresponding cap 36, whereupon the spring and its adjusting means may be removed as a unit.

30 The operation of my device will be apparent from the foregoing description. It is only desired to point out that by this means a log may be engaged before the carriage has come to a stop, whereupon the part 4 of the log turning arm will merely be deflected, and may during this deflection 45 operate to turn the log in the usual manner. By providing a yielding joint in the log turning arm the danger of breakage is greatly minimized. If, however, breakage should occur, in order to replace the broken 50 part, which would ordinarily be the part 4, it is only necessary to remove the pivot pin 34 and to slack off on the pressure of the springs 5 by screwing up the adjusting nuts 38 or by removing the caps 36. It is then 55 a simple matter to insert a new part 4 and

to readjust the tension of the springs. Such an operation would require but a few minutes and no special tools other than a wrench.

What I claim as my invention is:

1. In combination, means for supporting a log, and a two-part arm movable transversely of and over a log resting upon said support to turn the log about its longitudinal axis, said arm comprising a supporting part movable only in a plane and a log engaging part deflectable laterally of said plane and along said log axis. 75

2. In combination, means for supporting a log, and a two-part arm movable to turn a log resting upon said support about its longitudinal axis, said arm being under tension during the log turning operation and comprising a supporting part movable only in a plane and a log engaging part deflectable laterally of said plane and along said log axis. 80

3. In a log turner, a log turning arm formed in two parts, the outer or log-engaging part being pivoted at its inner end upon the inner or supporting part, to be movable relative thereto transversely of the arm, and spring means interposed between the inner and outer parts to maintain them normally in predetermined relationship. 90

4. In a log turner, a log turning arm formed in two parts, the outer or log-engaging part being pivoted at its inner end upon the inner or supporting part, to be movable relative thereto transversely of the arm, spring means interposed between the inner and outer parts to maintain them normally in predetermined relationship, and means for relieving said outer part from the action of said spring means. 100

5. In a log turner, a log turning arm formed in two parts, the outer or log-engaging part having a portion of a pivot bearing between its ends, the inner or supporting part having complementary portions of a pivot bearing at its outer end engageable with those of the log-engaging part, and compression springs interposed between the supporting part of said arm and each side of the inner end of the log-engaging part thereof, to permit yielding of the log-engaging part relative to the supporting part transversely of the arm. 110

6. In a log turner, a log turning arm formed in two parts, the outer or log-engaging part having a portion of a pivot bearing between its ends, the inner or supporting part having complementary portions of a pivot bearing at its outer end engageable with those of the log-engaging part, compression springs interposed between the supporting part of said arm and each side of the inner end of the log-engaging part thereof, to permit yielding of the log-engaging part relative to the supporting part. 120

transversely of the arm, and means for bodily removing said springs from the supporting part.

7. In a log turner, a two-part log-engaging arm, the inner part being movable in a plane perpendicular to the direction of movement of the log, and having a recess in its outer end, the outer part of said arm having its inner end received in said recess, a pivot pin passing through said inner and outer parts of the arm to permit swinging of the outer part relative to the inner part transversely of the arm, and springs secured in the inner part and bearing upon each side of the outer part inwardly of its pivot.

8. In a log turner, a two-part log-engaging arm, the inner part being movable in a plane perpendicular to the direction of movement of the log, and having a recess in its outer end, said inner part having also a pair of transversely-extending pockets opening into opposite sides of said recess, the outer part of said arm having its inner end received in said recess, a pivot pin passing through said inner and outer parts of the arm to permit swinging of the outer part relative to the inner part in the direction of movement of the log, and a compression spring seated in each of said pockets and bearing upon each side of the outer part inwardly of its pivot.

9. In a log turner, a two-part log-engaging arm, the inner part being movable in a plane perpendicular to the direction of movement of the log, and having a recess in its outer end, said inner part having also a pair of transversely-extending pockets opening into opposite sides of said recess, the outer part of said arm having its inner end received in said recess, a pivot pin passing through said inner and outer parts of the arm to permit swinging of the outer part relative to the inner part in the direction of movement of the log, a bolt passing out from each of said pockets, an external adjusting nut threaded upon each bolt, a spring retainer upon the inner end of each bolt, the inner ends of said bolts bearing upon opposite sides of the outer part inwardly of its pivot, and a compression spring interposed between each spring follower and the bottom of the pocket through which the bolt thereof passes.

10. In a log turner, a two-part log-engaging arm, the inner part being movable in a plane perpendicular to the direction of movement of the log, and having a recess in its outer end, said inner part having also a pair of transversely-extending pockets opening into opposite sides of said recess, a removable apertured cap closing the outer end of each pocket, a bolt passing through each of said apertures, an external adjusting nut threaded upon each bolt, a

spring retainer upon the inner end of each bolt, a compression spring surrounding each bolt and interposed between its cap and spring retainer, the outer part of said arm having its inner end received in said recess, a pivot pin passing through said inner and outer parts of the arm to permit swinging of the outer part relative to the inner part in the direction of movement of the log, the outer part of the arm, inwardly of the pivot, being interposed between and normally pressed upon from opposite sides by said springs, to retain the two parts of the arm normally rigid.

11. A log turner comprising a two-part arm one part of which is swingable only in a plane and the other part of which is deflectable laterally of said plane, said arm being subjected to tension during turning of a log.

12. A log turner comprising a log-engaging part formed to reach over a log and a supporting part normally substantially aligned with said log-engaging part, said supporting part being movable only in a plane and said log-engaging part being deflectable laterally of said plane.

13. A log turner comprising a two-part arm one part of which is engageable directly with the top of a log and the other part of which is formed to support said log-engaging part, said supporting part being swingable only in a plane toward and away from the log, and said log-engaging part being resiliently supported by said supporting part.

14. A log turner comprising a member swingable toward and away from a log about a fixed pivot, and a two-part arm pivotally associated with the swinging end of said pivoted member, one part of said arm being resiliently supported by the other part and said parts normally being in substantial alignment.

15. A log turner comprising a member movable about a lower pivot only in a plane transverse relatively to the direction of movement of the log, and an arm pivotally associated with the upper swinging extremity of said member, said arm being formed to engage the top of log and the log-engaging portion of said arm being deflectable laterally of said plane.

16. A log turner comprising a two-part arm one part of which is swingable only in a definite plane and the other part of which is normally substantially in line with said first mentioned part and is deflectable laterally of said plane, and a compression spring for normally maintaining said parts in alignment with each other.

Signed at Seattle, King County, Washington, this 8th day of December, 1922.

ULRICK J. RAYMOND.
